CLAIM

The ornamental design for a wall mounted key holder mail sorter organizer, as shown and described.

DESCRIPTION

FIG. 1 is a front and left perspective view of a wall mounted key holder mail sorter organizer, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the figures represent portions of the wall mounted key holder mail sorter organizer that form no part of the claimed design.
